J. K. OELSLAGER.
SHAKER AND TANK HEATER,
APPLICATION FILED MAR. 29, 1919.

1,330,717.

Patented Feb. 10, 1920.

Inventor.
J. K. Oelslager.

By *A. Murphy Jr.* Attorney.

UNITED STATES PATENT OFFICE.

JOHN K. OELSLAGER, OF INGALLS, INDIANA.

SHAKER AND TANK-HEATER.

1,330,717.

Specification of Letters Patent. Patented Feb. 10, 1920.

Application filed March 29, 1919. Serial No. 286,024.

To all whom it may concern:

Be it known that I, JOHN K. OELSLAGER, a citizen of the United States, residing at Ingalls, in the county of Madison and State 5 of Indiana, have invented certain new and useful Improvements in Shakers and Tank-Heaters; and I do hereby declare the following to be a full, clear, and exact description of the invention, such as will enable 10 others skilled in the art to which it appertains to make and use the same.

This invention relates to tank heaters, and the primary object of the invention is to provide an improved means for shaking 15 grates, so as to permit the ashes to be readily dislodged therefrom.

Another object of the invention is to provide an improved means for mounting the shaker rod in the tank heater so that the 20 same may be quickly and readily removed therefrom when so desired.

A further object of the invention is to provide an improved tank heater having an inclined chute for permitting the ashes to 25 be readily removed from the heater, the shaker being mounted in an offset guideway formed in the chute, so as not to interfere with the removal of ashes from the heater.

30 A further object of the invention is to provide an improved tank heater having the upper portion thereof so formed, that the entire heater can be immersed in the water in the tank, so that a maximum amount of 35 heat radiating surface may be engaged by the water.

A still further object of the invention is to provide an improved tank heater of the above character which is durable and efficient 40 in use, one that is simple and easy to manufacture, and one that can be placed upon the market at a reasonable cost.

With these and other objects in view the invention consists in the novel construction, arrangement and formation of parts, 45 as will be hereinafter more specifically described, claimed and illustrated in the accompanying drawings, forming a part thereof, in which:

50 Figure 1 is a vertical longitudinal section through the improved tank heater.

Fig. 2 is a section taken on the line 2—2 of Fig. 1.

Fig. 3 is a detail view of the shaker rod.

55 Fig. 4 is a detail section taken on the line 4—4 of Fig. 1.

Referring to the drawings in detail, wherein similar reference characters designate corresponding parts throughout the several views, the numeral 1 indicates the improved tank heater which includes the body 2 having the upper cylindrical portion 3 and the lower substantially rectangular portion 4, which forms the ash pit. The upper end of the body 2 is dome-shaped and provided with a smoke outlet 5. An annular flange 6 is formed around the smoke outlet and receives an ordinary stove pipe 7, having a damper 8 formed therein. An inner flange 9 is formed on the inner surface 70 of the body 2 intermediate the cylindrical portion 3 and the rectangular portion 4 thereof, and the flange receives the grate 10 and forms means for permitting the grate to be moved. An inwardly extending pin 75 11 is carried by the body 2 and engages the upper surface of the grate at the rear end thereof and prevents accidental displacement of the grate. The grate 10 is provided with a radially extending lug 12, which is 80 formed diametrically opposite the pin 11 and this lug extends outwardly of the body 2 into the inclined chute 13, which extends upwardly and outwardly from the lower portion 4 of the body and this chute 85 communicates with the ash pit and forms means whereby the ash pan 14 may be readily removed therefrom. The lug 9 is bifurcated as at 12 for receiving the lower end of the shaker rod 15, which will be hereinafter 90 more fully described.

The rear wall of the chute 13 is provided with an outwardly extending offset portion 16, which forms a guideway for receiving the shaker rod 15 and also forms means 95 whereby the shaker rod is positioned in rear of the inner face of the rear wall, so that the ash pan may be readily removed without contacting with the shaker rod or the lug 12. A supporting plate 17 extends transversely 100 across the guideway 16 adjacent to the lower end thereof and is spaced from the rear wall of the guideway, and the upper edge thereof is provided with an inwardly extending notch 18, which receives the cylindrical bearing lug 19 formed on the shaker rod and this plate forms means for holding the shaker rod in correct operative position and permits the same to be readily oscillated 105 for shaking the grate.

The shaker rod 15 has the lower end thereof inclined upwardly, as at 20, and gradually 110

tapered toward the end thereof so as to permit the same to be readily inserted in the bifurcated portion of the lug 12. The shaker rod 15 is slightly enlarged adjacent to the 5 inclined end and the cylindrical bearing 19 is formed on this portion. The inclined end 20 of the shaker rod conforms to the configuration of the lower portion of the meeting surface of the cylindrical body 3 and the off- 10 set enlargement 16. The upper portion of the shaker rod 15 forms an operating handle whereby the same may be readily grasped so that it can be swung on the supporting plate 17 and shake the grate. The upper end of 15 the shaker rod 15 ends adjacent to the upper end of the chute and in a convenient position whereby the same may be readily grasped.

A removable cap 21 is provided for the upper open end of the chute 13 and the cap 20 is provided with a reduced extension 22 for engaging the offset enlargement 16. The cap is provided with a pair of draft openings 23, and a slide plate 23 is mounted in the guideway 24 formed on the upper edge 25 of the cap 21 and this slide has a pair of openings 24' formed therein which are adapted to register with the openings formed in the cap 21 when the plate is operated, so as to permit the entrance of air into the 30 chute and below the grate when so desired. The movement of the slide 23 is limited in the guide way 24, by means of a depending pin 27 carried by the slide, which is slidably received in a slot 28 formed in the 35 cap 21.

An angular chute 25 communicates with the body 2 adjacent to the upper end thereof and a suitable cover 26 is provided for the same. The chute provides means where- 40 by fuel may be fed into the heater.

As clearly shown in Fig. 1 of the drawings the heater is to be placed directly in the tank which is to be heated, so that the water therein may readily circulate around the 45 outer surface of the heater.

From the foregoing description it can be

seen that an improved means is provided for operating the grate which is so positioned in relation to the ash removing chute, that the same does not interfere in any way whatso- 50 ever with the removal of the ashes.

In practice, I have found that the form of my invention illustrated in the accompanying drawings and referred to in the above description, as the preferred embodiment, is 55 the most efficient and practical; yet realizing the conditions concurrent with the adoption of my device will necessarily vary, I desire to emphasize that various minor changes in details of construction, proportion and ar- 60 rangement of parts may be resorted to, when required without sacrificing any of the advantages of my invention as set forth.

What I claim as new is:

A tank heater comprising a body, a grate 65 rotatably mounted in the body, an ash pit arranged below the grate, an outlet pipe communicating with the upper portion of the body, an inclined chute extending upwardly from and communicating with the 70 ash pit, a cover for this chute, a longitudinally extending offset formed on the rear wall of the chute, and a rearwardly extending bifurcated lug formed on the grate and extending into the offset portion of the chute, 75 a transversely extending plate secured in the offset portion and spaced from the rear wall thereof, and a shaker rod arranged to be positioned in the offset portion of the chute, the lower end of said rod being tapered and ar- 80 ranged to detachably fit in the bifurcated portion of said lug, and a cylindrical bearing pin formed on said shaker rod adjacent to the lower end thereof and arranged to detachably fit in said notch, as and for the 85 purpose specified.

In testimony whereof I affix my signature in presence of two witnesses.

JOHN K. OELSLAGER.

Witnesses:

WM. P. RANDALL,
MARY E. RANDALL.
